NUMERICAL CONTROL MACHINE

Warren Ponemon, Oyster Bay, N.Y., assignor to
Autonumerics, Inc., Westbury, N.Y.

Filed Aug. 18, 1971, Ser. No. 172,952

Term of patent 14 years

Int. Cl. D14—02

U.S. Cl. D26—5 C

FIG. 4

FIG. 2

FIG. 1

FIG. 3

FIG. 1 is a front elevational view of a numerical control machine showing my new design;

FIG. 2 is a left side elevational view thereof;

FIG. 3 is a rear elevational view thereof; and

FIG. 4 is a top plan view.

The side opposite that shown is a mirror image of the side that is shown.

I claim:

The ornamental design for a numerical control machine, substantially as shown and described.
